(57) **CLAIM**

The ornamental design for an antenna enclosure, as shown and described.

DESCRIPTION

FIG. 1 is a perspective view of an antenna enclosure showing our new design;

FIG. 2 is a right side view thereof;

FIG. 3 is a left side view thereof;

FIG. 4 is a bottom plan view thereof;

FIG. 5 is a top view thereof;

FIG. 6 is a front view thereof; and,

FIG. 7 is a rear view thereof.

The broken lines showing an exemplary connector to which the antenna enclosure may be coupled are included for the purpose of illustrating an environment of the antenna enclosure and form no part of the claimed design.
